(57) **CLAIM**

The ornamental design for a compound applicator, as shown.

DESCRIPTION

FIG. 1 is a top side perspective view of our new compound applicator;

FIG. 2 is a top plan view thereof;

FIG. 3 is a bottom plan view thereof;

FIG. 4 is a front side elevation thereof on an enlarged scale;

FIG. 5 is a rear side elevation thereof;

FIG. 6 is a right side elevation thereof, the left side being identical thereto;

FIG. 7 is a top side perspective view of a modified embodiment thereof;

FIG. 8 is a top plan view of the modified embodiment thereof;

FIG. 9 is a bottom plan view of the modified embodiment thereof;

FIG. 10 is a front side elevation of the modified embodiment thereof on an enlarged scale;

FIG. 11 is a rear side elevation of the modified embodiment thereof; and,

FIG. 12 is a right side elevation of the modified embodiment thereof, the left side being identical thereto.

FIGS. 4 and 10 are on an enlarged scale to more clearly show the curvature of the bottom.

The broken lines in FIGS. 4 and 10 in the drawings depict portions of the compound applicator that form no part of the claimed design.
